UNITED STATES PATENT OFFICE

146,100

DESIGN FOR A FACE PLATE FOR AIR CONDITIONERS

Bryant Essick, Los Angeles, Calif.

Application October 10, 1945, Serial No. 122,707

Term of patent 7 years

(Cl. D62—4)

To all whom it may concern:

Be it known that I, Bryant Essick, a citizen of the United States, residing in the city of Los Angeles, county of Los Angeles, and State of California, have invented a new, original, and ornamental Design for a Face Plate for Air Conditioners, of which the following is a specification, reference being had to the accompanying drawing, forming a part thereof.

Fig. 1, of the drawing is a perspective view of the face plate for air conditioners, showing my new design. Fig. 2 is a horizontal sectional view of the face plate taken through the center of the round opening in the center of the plate.

I claim:

The ornamental design for a face plate for air conditioners, as shown.

BRYANT ESSICK.
